UNITED STATES PATENT OFFICE.

JOHN W. LAUREN, OF STERLING, ILLINOIS, ASSIGNOR, BY MESNE ASSIGNMENTS, TO RAYMOND BROS. ENGINEERING CO., OF CHICAGO, ILLINOIS, A CORPORATION OF ILLINOIS.

FURNACE.

Application filed July 26, 1922. Serial No. 577,519.

To all whom it may concern:

Be it known that I, JOHN W. LAUREN, a citizen of the Republic of Finland, and a resident of Sterling, in the county of Whiteside and State of Illinois, have invented certain new and useful Improvements in a Furnace; and I do hereby declare that the following is a full, clear, and exact description of the same, reference being had to the accompanying drawings and to the numerals of reference marked thereon, which form a part of this specification.

This invention relates to a furnace in which powdered coal is adapted to be burned.

As these furnaces are now constructed, the fire box occupies the lower front part of the furnace, the flames ascending and passing eventually to the upper rear portion of the furnace, and the cinders settling upon the rear ledge. A large quantity of cinders, especially when powdered coal is used, collects upon this rear ledge. In time, these cinders are likely to obstruct the flames in the ways around the water flues or pipes or partly insulate the same from the flames.

It is an object of this invention to overcome the above noted objection by making provision for the escape of these cinders, and returning the same to the ash pit in the bottom of the fire box.

Other objects and advantages arising from the construction will become more apparent from the following description and disclosures.

This invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is a vertical longitudinal section of a furnace embodying this invention.

Figure 2 is a horizontal section through the furnace substantially upon the line 2—2 of Figure 1.

Figure 3 is a vertical transverse section through the furnace substantially upon the line 3—3 of Figure 1.

As shown on the drawings:

In the drawings, there is illustrated a

furnace adapted for burning powdered coal comprising the front wall 1, the side walls 2, the rear wall 3 of the fire box, the rear vertical wall 4 and the bottom 5 of the fire box which usually consist of fire brick. The furnace may consist of any usual known construction having the pipes P for admitting the powdered coal and the air pipes Q connected therewith as usual.

A boiler 60 of usual construction is supported in the top of the furnace which boiler 65 communicates with the usual water heating pipes 7 in the furnace.

Between the rear wall 3 of the fire box and the rear wall 4 there is usually a horizontal surface such as 6 upon which those 70 cinders collect which do not pass among the water tubes 7. When powdered coal is used, a large quantity of cinders float up through the furnace and settle upon the horizontal surface or ledge 6 and tend to 75 clog the ways between the water tubes. My invention is designed to overcome this defect by forming chutes from the horizontal ledge 6 to the bottom of the fire box through which the cinders may pass to the bottom of 80 the fire box. In the present instance, a pair of inclined chutes or passages 8 and 9 are formed in the rear wall of the fire box from the top of the ledge 6 to the lower rear corner of the fire box; the rear wall being 85 sufficiently thick for this purpose. Closures 10 are preferably placed across the lower ends of the chutes upon a rod 11 supported in the rear wall 3 and extending beyond one wall and equipped with an operating handle 90 12. The cinders which usually collected on the ledge 6 will now pass down the chutes 8 and 9 by gravity and rest against the closures 10 which may be periodically opened 95 by turning the crank 12 in the proper direction to permit the cinders to pass into the fire box.

It will accordingly be apparent that in a furnace involving this invention, the water flues or pipes are always kept free from having cinders pile therearound, and that the cinders are returned to the ash pit through the chutes and may periodically be removed from the furnace.

I am aware that numerous details of construction may be varied through a wide range without departing from the principles of this invention, and I therefore do not

purpose limiting the patent granted, otherwise than necessitated by the prior art.

I claim as my invention:

- 5 1. In a furnace, a fire-box, and a water-tube boiler supported above the rear portion thereof, the fire-box having a rear wall which slopes upwardly and rearwardly to direct the products of combustion toward and between the boiler tubes, this rear wall having upwardly flaring open ended passages therein, the upper ends of which receive cinders and ash from the stream of gases passing thereover, and the lower ends of which open into the bottom of the fire-box, and 10 discharge the cinders thereinto.
- 15 2. In a furnace, a fire-box, and a water-tube boiler supported above the rear portion thereof, the fire-box having a rear wall which slopes upwardly and rearwardly to direct the products of combustion toward and between the boiler tubes, this rear wall having upwardly flaring open ended passages therein, the upper ends of which receive cinders and ash from the stream of gases passing thereover, and the lower ends of which open into the bottom of the fire-box, and 20 discharge the cinders thereinto.
- 25 3. In a furnace, a fire-box, and a water-tube boiler supported above the rear portion thereof, the fire-box having a rear wall which slopes upwardly and rearwardly to direct the products of combustion toward and between the boiler tubes, this rear wall having upwardly flaring open ended passages therein, the upper ends of which receive cinders and ash from the stream of gases passing thereover, and the lower ends of which open into the bottom of the fire-box, and discharge the cinders thereinto, 25 closures for the bottom of these passages,

and means for operating these closures from outside the furnace.

- 30 3. In a furnace, a fire-box having front and side walls and a cover arch for the forward portion of the fire-box, and a thick upwardly and rearwardly inclined rear wall having upwardly flaring open-ended passages therein, the lower ends of which communicate with the bottom of the fire-box, a water tube boiler above the fire-box with the water-tubes supported at their front ends on the cover arch, and supported intermediately and at their rear ends on the rear wall, the flaring upper ends of the passages being beneath the rear portion of the tubes to receive cinders deposited from the gas stream flowing therebetween, which cinders are discharged through the passages back into the bottom of the fire-box.
- 35 40 45

In testimony whereof I have hereunto subscribed my name in the presence of two 50 subscribing witnesses.

JOHN W. LAUREN.
